TEACHING MACHINE

Michael J. Freeman, 100 De Haven Drive,
Yonkers, N.Y. 10703

Filed Feb. 19, 1974, Ser. No. 443,219

Term of patent 14 years

Int. Cl. D19—07

U.S. Cl. D19—60

FIG. 2.

FIG. 7.

FIG. 1.

FIG. 1 is a front elevational view of a teaching machine embodying my new design;

FIG. 2 is a side elevational view of the teaching machine of FIG. 1 from one side thereof;

FIG. 3 is a rear elevational view of the teaching machine of FIG. 1;

FIG. 4 is a side elevational view of the teaching machine of FIG. 1 from the opposite side to that of FIG. 2;

FIG. 5 is a bottom plan view of the teaching machine of FIG. 1; and

FIG. 6 is a bottom plan view of the teaching machine of FIG. 1; and

FIG. 7 is a fragmentary front elevational view of the head of the teaching machine of FIG. 1 showing the

mouth in an alternative arrangement provided by movement of the indicators therein.

I claim:

The ornamental design for a teaching machine, as shown and described.
